UNITED STATES PATENT OFFICE.

JOHN W. HOOSER, OF DALLAS, TEXAS.

DESIGN FOR AN ENGINE-MANIFOLD FOR INTERNAL-COMBUSTION MOTORS.

53,269.

Specification for Design.

Patented May 6, 1919.

Application filed October 22, 1917. Serial No. 197,966. Term of patent 7 years.

To all whom it may concern:

Be it known that I, JOHN W. HOOSER, a citizen of the United States, residing at Dallas, in the county of Dallas and State of Texas, have invented a new, original, and ornamental Design for Engine-Manifolds for Internal-Combustion Motors, of which the following is a specification, reference being had to the accompanying drawings, forming part thereof.

The figure is a side elevation of the engine manifold, showing my new design.

I claim;

The shape and design for an engine manifold for internal combustion motors, as disclosed.

JOHN W. HOOSER.
